UNITED STATES PATENT OFFICE

HANS JADE, OF SAN FRANCISCO, CALIFORNIA

TOY BRIDGE

Application filed September 29, 1926. Serial No. 138,467.

This invention relates to improvements in toy bridges, and has particular reference to a mechanical toy bridge.

The principal object of this invention is to produce a toy bridge for use in connection with toy trains or the like, whereby the action of a swinging bridge of the turn-table type will be simulated.

Another object of the present invention is to produce a toy bridge which is simple and therefore cheap to manufacture, and well within the purchase price of the average user.

A further object is to produce a toy of this character which is neat and pleasing in appearance.

Other objects and advantages will be apparent during the course of the following description.

In the accompanying drawings forming a part of this specification, and in which like numerals are employed to designate like parts throughout the same,

Figure 1 is a top plan view of my toy,

Figure 2 is a side elevation of Figure 1,

Figure 3 is a horizontal cross section taken on the line 3—3 of Figure 5,

Figure 4 is a horizontal cross section taken on the line 4—4 of Figure 5,

Figure 5 is a vertical cross section taken on the line 5—5 of Figure 3,

Figure 6 is a fragmentary detail view showing the latch mechanism, and

Figure 7 is a fragmentary detail view showing the gate operating mechanism.

In the accompanying drawings wherein for the purpose of illustration is shown a preferred embodiment of my invention, the numeral 5 designates a frame adapted to simulate a bed of a stream having bridge abutments 6 and 7 secured thereto, while at 8 I have illustrated a pier common to all turn-table type of bridges. This pier encloses a gear mechanism operated through the medium of a spring, which spring is tensioned over a winding shaft 9 on which a key is placed.

If desired, a bell 11 may be employed which bell is contacted by a striker 12 for the purpose of giving an audible signal during the operation of the bridge.

The gear mechanism is adapted to drive a

shaft 13 having a disc 14 on the lower portion thereof and an arm 16 upon its upper extremity. The disc 14 is provided with notches 17 on the periphery thereof which are adapted to be engaged by a dog 18 pivoted as 55 at 19. A spring 21 serves to normally keep the dog in engagement with the periphery of the disc.

A lever 22 positioned upon one of the abutments is connected by a link 23 to a bell crank 60 24, which bell crank in turn is adapted to contact a push rod 26. The push rod in turn engages one end of the lever 18.

A disc 27 is secured to the lower extremity of the shaft 13 and has downwardly projecting cams 28 which are adapted to contact an arm 29 carried upon the shaft 31, which shaft has levers 32 at each end thereof. These levers are in turn connected by links 33 to gates 34 pivotally supported on each of 70 the abutments.

A shaft 36 is positioned in the pier 8 and has a lever 37, which lever is connected by a link 38 to the crank 16.

Mounted upon the shaft 36 is a bridge 75 portion 39, which bridge portion simulates the standard type of turn-table bridge, and may or may not have railroad tracks positioned thereon.

The manner of operating my bridge is as 80 follows:—

Assuming that it is desired to operate the same and that the spring has been tensioned the lever 22 is moved, which in turn pushes upon the end of the latch 18 withdrawing the 85 same from one of the notches 17 which permits the spring of the gear train to function, after which the shaft 13 will make a quarter revolution of shaft 36 through the link connection 38 to the lever 37 and will cause the bridge to make a quarter turn. Immediately upon the initial movement of the shaft 13, the cam 28 striking the arm 29 will cause the gates adjacent each end of the 90 bridge to go down.

The second operation of the lever 32 will cause the bridge to return to its normal position and the gates to be raised.

It will thus be seen that I have provided a 100

very simple mechanism for accomplishing the objects above set forth.

It is to be understood that the form of my invention herewith shown and described is to be taken as a preferred example of the same and that various changes relative to the size, material, shape and arrangement of parts may be resorted to without departing from the spirit of the invention or the scope 10 of the subjoined claim.

Having thus described my invention, I claim:—

In a toy of the character described, a pair of portable spaced abutments connected to each other, a pier fixedly positioned between said abutments, a bridge portion pivotally supported on said pier and adapted to be rotated into and out of contact with said abutments, a gear mechanism positioned within 15 said pier, and adapted to rotate said bridge, gates positioned on said abutments, a shaft extending between said abutments, means for 20 rocking said shaft when said bridge is actuated and means for transmitting said rocking motion from said shaft to said gates.

In testimony whereof I affix my signature.
HANS JADE.
